UNITED STATES PATENT OFFICE.

WILLIAM THOMSON, OF GLASGOW, COUNTY OF LANARK, SCOTLAND.

GALVANOMETER.

SPECIFICATION forming part of Letters Patent No. 416,654, dated December 3, 1889.

Application filed December 8, 1887. Serial No. 257,320. (No model.) Patented in England July 10, 1886, No. 9,016; in France May 23, 1887, No. 183,730, and in Belgium May 25, 1887, No. 77,594.

To all whom it may concern:

Be it known that I, Sir WILLIAM THOMSON, knight, of Glasgow, in the county of Lanark, Scotland, have invented certain new and useful Improvements in Galvanometers, (for which Letters Patent have been granted to me in Great Britain, No. 9,016, dated July 10, 1886; in France, No. 183,730, dated May 23, 1887, and in Belgium No. 77,594, dated May 25, 1887,) of which the following is a specification.

My invention relates to apparatus for measuring the efficiency of electric currents; and it consists in certain features of novelty in apparatus designed for use in steady and undisturbed places.

The apparatus is an electro-dynamic balance consisting, essentially, of a soft-iron core or movable coil made temporarily magnetic by the current to be used by means of a fixed coil or coils through which the current temporarily passes. For a standard instrument not liable to change with time I prefer a movable coil or coils mounted on a gravity-balance and affected by corresponding fixed coil or coils and special arrangements for putting on or taking off weights.

My invention will be fully understood by reference to the accompanying drawings, in which—

Figure 1 is a front end elevation of the simple form of my invention as intended for land use. Fig. 2 is a vertical longitudinal section on line 2 2, Fig. 7. Fig. 3 is a vertical transverse section on line 3 3, Fig. 8. Fig. 4 is a plan view of the simple form. Fig. 5 is a side elevation of a modification in which the beam is mounted near its center and has a coil at each end. Fig. 6 is a plan of the same. Fig. 7 is a side elevation showing modifications in the sliding weights. Fig. 8 is a plan view of the same. Fig. 9 is a further modification showing a balance suitable for light work.

i represents the beam of the balance, which may be either supported on knife-edges or suspended, in the manner to be hereinafter described, near one end, and provided with a coil *j* at the other end, the weight of the coil and beam being counterpoised by a weight on the end of the latter opposite to the coil. In this form I sometimes use a set of weights

of any suitable kind, which may occupy the space, as indicated in Fig. 7, and be supported by the stirrup *p*. This stirrup *p* is supported upon knife-edges *q*, as shown in Fig. 2. 55

The suspended coil *j* is acted upon by one or more (preferably two) fixed coils *x*. (See Figs. 2 and 4.) These coils *x* may be either flat and of approximately the same mean diameter as the suspended coil, and arranged as clearly shown in Figs. 5 and 6, or the coils may be of comparatively small depth in the direction of their diameters and of smaller cross-sections than the internal diameters of the suspended coils and fixed coaxially with them, so that their planes being parallel and nearly horizontal and at the proper distances apart give convenient electro-dynamic stability. The latter form of fixed coils is preferred when the instrument is intended to be used to measure powerful currents, and in such cases the coils are, for direct-current measurements, made of copper ribbon of such breadth and thickness as is convenient for carrying without inconveniently heating the maximum current to be measured. 75

For alternating-current measurements both movable and fixed coils are constructed of twisted copper rope made up of sufficiently thin insulated wire to prevent any disturbance which might result from the unequal distribution of the current over the cross-section of the conductor. The twist in the rope should be such that there will be an integral number of twists in the rope for each turn round the coil. The section of the rope is either round or flattened to a ribbon, as is found most suitable in different cases. The coils are preferably wound on massive copper (or other metal) plates *y*, forming the base-plate and frame-work of the instrument. When the instrument is intended to measure alternating currents, these bobbins and plates are so cut as to prevent the circulation of induced currents round them, and are supported, when necessary, upon insulated material. These plates, in consequence of their large surface and high thermal conductivity quality, facilitate the carrying away of the heat generated in the coils by the passage of the current, and hence prevent to a certain extent error 95 100

from this cause due to change of dimensions of the beam or upward currents of air.

The preferred form for suspending the beam i is shown in Figs. 1 to 3. It consists of two flat ligaments z , formed of a sufficient number of very fine wires laid side by side in the same plane. The two ends of this ligament are securely soldered to semi-cylindrical pieces $a' b'$, the upper pair a' of the pieces being fixed to the frame-work through the pillars c' and cross-pieces d' , and the lower pair b' to the beam of the balance. The beam is prevented from taking too much horizontal motion in the direction of its length by means of forks e' and steady-pins f' , whereby the danger of bending the ligament z , and consequently changing the zero-reading of the instrument, is avoided. The pins f' are so placed as to be out of contact with the sides of forks e' when the instrument is in use.

In Figs. 5 to 8 I have shown another form of my invention which I prefer to use when the highest possible accuracy is desired. In this form the beam of the balance is suspended from a point near the center of its length. A coil j is attached to both ends of the beam, and each of these coils is acted upon by one or more fixed coils x , as will be hereinafter described.

For the weights and lifters of the first form I substitute in this form either scale-pans and weights or a slide g' , fixed to the side of the beam i , along which weights h' may be moved by sliders i' , so as to balance the electro-dynamic forces produced by the currents in the coils. The sliders i' may be of the form shown in Figs. 5 and 6 or of the modified form shown in Figs. 7 and 8.

In the form shown in Figs. 5 and 6 a rigid frame furnished with three feet j' slides along a horizontal platform fixed in front of the instrument, said platform having formed along its length a V-shaped groove, which forms a guide for two of the feet j' . The slider i' carries on it a pivoted frame k' , held in an upright position by light springs l' . An upright piece m' , forming part of the frame k' , passes through a recess in the weight, and when the weight is to be moved along the slide g' the frame k' is tilted over in the direction of motion and the whole frame moved until the weight is brought to the desired position, after which the frame k' is allowed to take an upright position and the bar m' assumes its position in the recess of the weight, as shown in Fig. 6, which leaves the weight clear and the balance free to move.

In the arrangement shown in Figs. 7 and 8 a pendant n' is substituted for the pivoted frame k' , and the slider is moved from one side or the other by threads o' , attached to the bottom of the pendant. When the weight has been moved to the desired position, the thread is left slack, and the pendant, by assuming a vertical position under the action of gravity, falls to the center of

the recess in the weight, which leaves the beam free. The weight on the right end of the slide is intended to be used as a counterpoise for the sliding weight when it is at its zero position, and also to give a convenient means for adjusting the beam of the balance to the zero position. For this purpose it is not necessary that the frame which carries the pendant should be movable, as the range of movement of said pendant can be made sufficiently great to give the required adjustment.

On the slide g' a scale of equal divisions is engraved and also a series of fine notches corresponding in position to the lines of a second scale p' , fixed to the frame-work of the instrument in a position above the beam and at the back of the slide. These scales allow the position of the weights upon the slide to be read off at any time. The numbers on the fixed scale p' are proportional to the square roots of the numbers on the scale g' , and are such that when the weight is brought to different positions, so as to balance the electro-dynamic force due to the different currents, equal differences of reading indicate equal differences of current. Side motion of the beam in this form of the instrument is prevented by the screws q' . End motion is prevented by similar screws fixed to the frame-work near the semi-cylindrical pieces b' .

The form of instruments for measuring light currents (shown in Figs. 5 and 6) has lighter and longer suspension-ligaments attached to the beam through a round central axis or trunnion, and is held from end movement by passing this trunnion through a square hole in upright piece r' , adjustably fixed to the base-plate of the instrument, or by two screws adjustably fixed on the two sides of the trunnion and guard-pieces fixed to the frame-work above the trunnion to prevent the ligament from being so much slackened as to damage it. The arrangement with graduated slide having self-relieving pendants to move the sliders is also applicable to ordinary weighing-balances.

When scale-pans are employed, I prefer, for convenience, to use two scale-pans at each end of the beam, one hung from each of the four prolongations or knife-edges at the ends of the transverse diameters of the coils.

When no current is flowing through the coils, the whole or greater part of the weights should be placed on the scale-pan nearest the operator and balance restored by weight placed in the most distant pan at the other end of the beam. The strength of current flowing at any time through the coils is estimated by the amount of weight which has to be transferred from one end of the beam to the other in order to restore equilibrium.

Another modification of the balance which is suitable for a voltmeter is shown in Fig. 9. This form measures moderate changes of current by the movement of an index over a ver-

tical scale. It differs from those already described in having but one movable coil j and one fixed coil x and in the addition of a light index s' , resting on knife-edges at t' and connected to the movable coil by a link u' . Any motion up or down of the coil j causes the index to turn on its knife-edges and register the amount on scale v' . The requisite stability to allow the instrument to have a sufficient range is furnished by the variation of the electrical forces between the two coils as their distances apart vary. The necessary gravitational force against which the electro-dynamic force acts is obtained by adding the necessary weight to the movable coil. It is preferable to place this weight as nearly as possible at the transverse diameter of the coil; but in practice I have found it more convenient to place the weight (having the form of a round rod) in a V-shaped trough fixed to the outer end of the coil, with its length at right angles to the length of the balance-beam. This form of balance is specially suitable in conjunction with resistance-coils to indicate the changes in potential which are being maintained on an electric circuit.

w' in Fig. 15 represents a resistance-coil attached to the under side of the base-plate of the instrument.

Having thus described my invention, the following is what I claim as new and desire to secure by Letters Patent:

1. In an electro-dynamic balance, substantially as herein described, the combination of beam i , suitably suspended at one end, and coil j at the other end, with stationary coil x , surrounded by coil j , and suitable weights for attaching to said beam, whereby the dynamic force of the currents passed through said coils may be balanced and the difference in their potentials measured, as set forth.

2. In an electro-dynamic balance, substantially as herein described, the combination of the beam i , the coil j , and ligamental suspension for the beam, whereby the current is led

into and out of the circuit of the movable coil through said ligamental suspension, with stationary coil x and stirrup p for holding the weights, as set forth.

3. In an electro-dynamic balance, the combination of the beam i and coils j and x with the graduated slide g , attached to the beam and adapted to support a sliding weight, whereby the electrical forces can be balanced and their relative potentials measured, as hereinbefore described. 50

4. In an electro-dynamic balance, the combination of the balance-beam and the movable and stationary coils with the massive copper or other metallic base-plates and supporting-bobbins, whereby the cooling of the coils is effected, as hereinbefore described. 60

5. In an electro-dynamic balance, the combination of the coils and beam with a scale of equal divisions and a square-root scale, 65 whereby a direct reading of the strength of the current in circuit may be had, as hereinbefore described.

6. In an electro-dynamic balance, the combination of the coils, the beam, and a scale 70 with two slides carrying weights supported on said scale, one of which slides is adapted to adjust the zero of the balance and the other to measure the current, as hereinbefore set forth. 75

7. In an electro-dynamic balance, the combination of the coils, the beam, and scale on said beam with self-relieving pendants for moving the weights along the slide, as hereinbefore described. 80

In testimony whereof I have signed my name to this specification in the presence of two subscribing witnesses.

WILLIAM THOMSON.
